US00D903768S

(12) **United States Design Patent** (10) Patent No.: **US D903,768 S**
(45) Date of Patent: **** Dec. 1, 2020**

(54) **CONTROLLER FOR COMPUTER**

(71) Applicant: **NINTENDO CO., LTD.**, Kyoto (JP)

(72) Inventors: **Hitoshi Tsuchiya**, Kyoto (JP);
Fumiyoishi Suetake, Kyoto (JP); **Yui**
Ehara, Kyoto (JP); **Yuko Zenri**, Kyoto
(JP); **Junichiro Miyatake**, Kyoto (JP);
Tetsuya Akama, Kyoto (JP)

(73) Assignee: **Nintendo Co., Ltd.**, Kyoto (JP)

(**) Term: **15 Years**

(21) Appl. No.: **29/645,672**

(22) Filed: **Apr. 27, 2018**

Related U.S. Application Data

(62) Division of application No. 29/595,214, filed on Feb. 27, 2017, now Pat. No. Des. 819,641.

(30) **Foreign Application Priority Data**

(57) **CLAIM**

The ornamental design for a controller for computer, as shown and described.

DESCRIPTION

FIG. 1 is a front side perspective view of a controller for computer showing our new design;

FIG. 2 is a front view thereof;

FIG. 3 is a back view thereof;

FIG. 4 is a top view thereof;

FIG. 5 is a bottom view thereof;

FIG. 6 is a right view thereof;

FIG. 7 is a left view thereof; and,

FIG. 8 is an enlarged view of the section indicated in FIG. 2.

The dash-dash broken lines show portions of the controller for computer that form no part of the claimed design.

The dash-dot broken lines depict the boundary of the claim and form no part of the claimed design.

1 Claim, 8 Drawing Sheets
